COMBINED CLOCK AND POWER TOOTHBRUSH HOUSING

Thomas H. Hayes, Roanoke, Va., assignor to Sunbeam
Corporation, Chicago, Ill., a corporation of Illinois

Filed Sept. 29, 1966, Ser. No. 4,085

Term of patent 14 years

(Cl. D42—7)

FIG. 1 is a front perspective view of a combined clock and power toothbrush housing showing my new design; FIG. 2 is a front elevational view thereof;

FIG. 3 is a top plan view thereof;

FIG. 4 is a left side elevational view thereof;

FIG. 5 is a sectional view taken on line 5—5 of FIG. 2; and,

FIG. 6 is an enlarged, fragmentary sectional view taken on line 6—6 of FIG. 3.

I claim:

The ornamental design for a combined clock and power toothbrush housing, as shown.
